BRACELET EXTENSION

Sven O. Myrberg, Providence, R. I., assignor to
Providence Stock Company, a corporation of
Rhode Island

Application December 17, 1934, Serial No. 757,807

2 Claims. (Cl. 24—71)

My present invention relates to the jewelry art, and has particular reference to the construction of extension devices for bracelets and watch straps.

5 Extension devices have heretofore been made with folding plates adapted to be releasably locked in folded position; and adjustments have been provided to permit changes in the overall length of the extension device to better fit the 10 bracelet or watch strap to the wrist of the wearer.

These adjustments have necessitated opening the bracelet or watch strap to change the setting of the adjusting mechanism; it is the principal object of my invention to devise a construction 15 which will facilitate and permit adjustment whether the extension device is in open or closed position.

It is a further object of my invention to provide an adjusting mechanism which is suitable 20 for use with thin and with narrow extension devices, whereby a relatively large extension and a substantial amount of adjustment is obtainable with extension devices that are extremely compact when in folded position.

25 It is an additional object of my invention to provide an adjustable extension device formed of a small number of sturdy and strong parts.

With these and other advantageous features in view, the invention consists of a novel arrangement of parts more fully disclosed in the 30 following detailed description, in conjunction with the accompanying drawing, and more particularly defined in the appended claims.

In the drawing,
35 Fig. 1 is a plan view showing the extension device in closed, adjusted position;

Fig. 2 is a side view of the extension device, the folding parts being in opened relation;

Fig. 3 is a rear view of the extension device, the 40 folding parts being extended;

Fig. 4 is a view similar to Fig. 1, but broken away to show the adjusting mechanism; and

Fig. 5 is a section on the line 5—5 of Fig. 4.

Referring to the drawing, the bracelet or 45 watch strap 10, preferably formed of separate links 11 hingedly connected together by hinges 12, includes an extension device 13. The extension device comprises a top plate 14 having side channels 15, in which a link 16 is slidably mounted, the link 16 being secured to one end of the bracelet 10, an intermediate plate 17 hinged to the top plate, and a base plate 18 hinged to the intermediate plate and secured to the other end of the bracelet 10.

55 As shown in Fig. 4, a plate 19 is mounted in the

top plate 14, the plate 19 having a central recess 20, one side of the recess being formed with a plurality of ratchet teeth 21. The link 16, see Fig. 3, has its end recessed to provide a spring bar 22 having a depending pawl 23 selectively engageable with the teeth 21 and a lateral extension 24 which extends out through a slot 25 provided in one wall 15 and is adapted to be engaged by a finger nail or the like. The link 16 has additional recesses 26, 27 and a cross bar 28, 10 to simulate bracelet links when the link is outwardly extended from the top plate.

The top plate side walls are provided with snap recesses 29, 30, and the base plate, which has side walls 31, is provided with cooperating snaps 32, 15 33, whereby the base plate and the intermediate plate may be releasably folded into the top plate, as shown in Fig. 5. A finger catch 34 is provided on the top plate, see Figs. 2 and 4, to facilitate 20 opening the extension device.

The operation of the novel construction may now be explained; with the device in closed position, the finger catch is lifted, and the extension device opened. The pawl is still engaged with a selected tooth, however, but may be released by 25 pressing the extension by a thumb nail or finger nail, thus moving the pawl away from the ratchet teeth and permitting a further longitudinal movement of the entire link to extend the same outwardly from the top plate, the extension moving in the slot 25, until the pawl engages the end of the central recess 20. When the extension is no longer pressed inwardly, the pawl reengages the ratchet teeth to prevent further outward movement of the link, while permitting inward movement until a desired overall length is obtained.

The described arrangement is suitable for 30 bracelets and watch straps of any type, whether link, mesh, leather, etc.; the parts are solid and 40 sturdy, and present a completely closed, attractive appearance. The adjusting mechanism permits a selective length setting whether the extension device is open or closed, and a further contraction after the extension device is folded 45 in closed relation.

Although the sliding link has been described as slidably engaging the top plate, it is obvious 50 that it may cooperate with the base plate, and that other desired changes in the arrangement, 55 number, and size of the parts and in their operation, may be made to conform to different designs of bracelets, within the spirit and the scope of the invention as defined in the appended 55 claims.

I claim:

1. In an extensible connector for bracelets, a member having side walls, a link slidably mounted in said member and extendible from one end thereof, one side wall of said member having a slit, and an element fixed in said member and having a longitudinal recess provided with a series of longitudinal disposed ratchet teeth, said link including a resilient arm provided with a pawl which extends at right angles to the plane of the link and is selectively engageable with said teeth, and a manually engageable part slidable in said side wall slot and operatively connected to said arm.
- 15 2. In an extensible connector for bracelets, a

member having side walls, a link slidably mounted in said member and extendible from one end thereof, one side wall of said member having a slit, and an element fixed in said member and having a longitudinal recess provided with a 5 series of longitudinal disposed ratchet teeth, said link including a resilient arm provided with a pawl which extends at right angles to the plane of the link and is selectively engageable with said teeth, and a manually engageable part slidable 10 in said side wall slot and operatively connected to said arm, the end wall of said recess serving as a limit stop abutment for said pawl.

SVEN O. MYRBERG. 15
